Primary Examiner — Jae Liang*Assistant Examiner* — Riya Salil Kamat(74) *Attorney, Agent, or Firm* — Foley & Lardner LLP(57) **CLAIM**

The ornamental design for a thrower as shown and described.

DESCRIPTION

FIG. 1 is a front perspective view of a thrower in accordance with our new design;

FIG. 2 is a back perspective view thereof;

FIG. 3 is an enlarged front perspective view of a scooper of the thrower;

FIG. 4 is a first side plan view of the scooper;

FIG. 5 is a second side plan view of the scooper;

FIG. 6 is a back plan view of the scooper;

FIG. 7 is a back plan view of the scooper;

FIG. 8 is a bottom plan view of the scooper; and,

FIG. 9 is a top plan view of the scooper.

The broken lines in the drawings illustrate portions of the thrower that form no part of the claimed design.

1 Claim, 6 Drawing Sheets(56)
